R. H. PARSONS,
ELECTRICALLY CONTROLLED DOOR LOCK FOR CARS.
APPLICATION FILED APR. 4, 1919.

1,405,623.

Patented Feb. 7, 1922.

Inventor
Raymond H. Parsons
By his attorney Samuel E. Darby

UNITED STATES PATENT OFFICE.

RAYMOND H. PARSONS, OF NEW YORK, N. Y., ASSIGNOR TO NATIONAL PNEUMATIC COMPANY, OF NEW YORK, N. Y., A CORPORATION OF WEST VIRGINIA.

ELECTRICALLY-CONTROLLED DOOR LOCK FOR CARS.

1,405,623.

Specification of Letters Patent. Patented Feb. 7, 1922.

Application filed April 4, 1919. Serial No. 287,385.

To all whom it may concern:

Be it known that I, RAYMOND H. PARSONS, a citizen of the United States, residing at New York, in the county of Bronx, State of New York, have made a certain new and useful Invention in Electrically-Controlled Door Locks for Cars, of which the following is a specification.

This invention relates to electrically controlled door locks for doors employed on street cars, interurban cars, subway or elevated trains, railway trains, or the like, and particularly to such cars or trains which are electrically operated.

The object of the invention is to provide an electrically controlled door lock which is simple in construction, efficient in operation, and economical of manufacture, and readily assembled, and which requires little or no attention in upkeep.

A further object of the invention is to provide an electrically controlled lock for doors which will effectively lock the door against accidental or deliberate opening while the car is in motion.

Other objects of the invention will appear more fully hereinafter.

The invention consists substantially in the construction, combination, location and relative arrangement of parts, all as will be more fully hereinafter set forth as shown by the accompanying drawing and finally pointed out in the appended claims.

Referring to the drawing:

Fig. 1 is a top plan view of a door lock mechanism employed in accordance with my invention.

Fig. 2 is a similar view showing same in its unlocked position.

Fig. 3 is a view in side elevation of the same with the parts in the position shown in Fig. 1.

Fig. 4 is a sectional view taken on the line 4, 4, Fig. 3, looking in the direction of the arrows.

Fig. 5 is a diagrammatic view of the circuit employed in accordance with my invention.

The same part is designated by the same reference character wherever it occurs throughout the several views.

In accordance with my invention I propose to provide a door lock for street cars, or other cars which are electrically driven, and to utilize the current supplied to the motor

of the car when the same is being propelled to lock the door against movement, accidental or otherwise. I further propose to utilize the established principle that when the car is coasting, or is moving due to its momentum, the driving motor being geared to the wheels and continuing therefore to rotate, acts as a generator of current, and I utilize the current thus generated when the car is coasting or moving under its own momentum to likewise lock the door in its closed position so that I thereby obtain a permanent electrically operated lock for the door which can only be unlocked or rendered inoperative when the car is standing still.

It is known to employ pneumatic motors for operating doors and to provide means for electrically controlling the control valve of the pneumatic motors when the car is in motion to prevent the actuation of the motor to open the door. A great many of the cars at present in use, however, are of the manually operated type, and it is principally to the manually operated doors of electrically driven cars that my present invention is directed, and in accordance therewith when the car is in motion I prevent manual or accidental operation of the manual control devices from securing its normal result of opening the door.

Doors on cars which are actuated directly or indirectly by the rotation of a door shaft are well known in the art and are the standard type of doors employed, and for the purpose of illustrating my invention I have applied the principles thereof to a rotating member which may be the actuating shaft of the door or it may be any shaft in the door operating mechanism which upon rotation effects the opening of the door. This shaft I have indicated at 1, and suitably located at the end thereof to rotate therewith I provide a disk 2 with a notch or jog 3 cut therein as shown. In practice I prefer to have the shaft 1 pass through a plate or support 4 which is mounted at the top of the door to be out of the way, unseen, and less apt to become accidentally or otherwise deranged. Pivotedly mounted on the plate 4, I provide a dog 5 with two arms 6 and 7. The dog 5 is a curved member held on a pin 8 carried by the plate 4 in any suitable manner, for example, by means of a cotter pin. The end 6 of dog 5 is adapted to fit into the jog 3 of the rotatable

disk 2. A spring 9 is fastened to a pin 10 on the plate 4 and a pin 11 on the leg 7 of the dog 5 to normally tend to project the leg 6 of the dog 5 into the jog 3 of the disk 2. Also mounted on the plate 4 is a suitable magnet 13 which may be of any desired type or construction, or as illustrated, the armature of which is a plate 14 pivotally carried by pin 15 journaled in frame 16. The end of the armature 14 is provided with a pin 17 which fits loosely in a yoke 18 which forms one end of an arm 19 pivotally mounted at 20 in the frame 16. A spring 21 is interposed between the frame 16 and the armature 14. From the foregoing construction it will be seen that the arm 19 is moved about its pivot upon actuation of the armature 14 but that its movement is slightly in advance of the armature 14 when 20 the armature is attracted towards the magnet and is slightly behind the movement of the armature 14 when the magnet is de-energized due to the pin and slot connection between the armature 14 and the arm 19 secured by means of the pin 17 and the yoke 18. The end of the arm 19 has secured thereto a block 20, which, when the magnet is energized, and as shown in Fig. 1, becomes positioned between the end of the leg 7 of the dog 5 and a stationary block 21 secured to the plate 4.

The operation of the device thus far described will be apparent. If the magnet 13 is energized the armature 14 and consequently the arm 19 is drawn into the position shown in Fig. 1 and thereupon counterclockwise rotation of the shaft 1 as indicated by the arrow is prevented because the end of the jog 3 bears against the leg 6 of dog 5 and the leg 7 of dog 5 bears against the movable lock block 20 and the fixed stop block 21, thereby preventing the rotation of the shaft 1. As soon, however, as the magnet is deenergized the shaft 1 is rotated counterclockwise as indicated by the arrow in Fig. 2. The jog 3 in the disk 2 causes the dog 5 to be rotated about its pivot 8 against the action of the spring 9 for the block 20 of the arm 19 has been drawn out of the path of the end of the leg 7 of the dog 5.

In the present equipment of street cars the "counter E. M. F." principle of the motor acting as a generator when the car is moving due to its own momentum has been utilized extensively in coasting recorders or time recorders in the manner shown and described in Letters Patent to Messrs. Hall and Hall, No. 1,201,041, dated October 10, 1916, and in Letters Patent to Messrs. Wade & Chappelle, No. 1,275,328, dated August 13, 1918, and it is therefore the present practice to employ a circuit arrangement somewhat similar to that shown in Fig. 5, wherein current is supplied from the third rail, trolley wire or the like, to line 30 where

it passes through solenoid 31 to the car motor by a conductor 32 (not shown). Thus if current is being utilized by the motor to propel the car the solenoid 31 raises its plunger 33 to establish circuit connection between contacts 34 and 35, one of which contacts, namely 34, is connected to the source through wire 30, and the other of which contacts is connected to the magnet 13. Thus it will be seen that when the car is being propelled by electric power the magnet 13 is energized to lock the door against opening. Likewise, when the current is not being supplied from line 30, and consequently the solenoid 31 is de-energized, the plunger 33 establishes circuit connection between contacts 36 and 37 so that the motor 38 being rotated generates current which is supplied through contacts 36, 37, to the magnet 13, thus preventing the door from being opened when the car is in motion and being propelled from the electric source. In both of the foregoing instances the magnet 13 is connected to ground in any suitable manner to establish the complete circuit.

Many modifications and changes in detail will readily occur to those skilled in the art without departing from the spirit and scope of my invention as defined in the claims, but having now set forth the object and nature of my invention and having shown and described a structure and arrangement embodying the principles thereof, what I claim as new and useful and of my own invention and desire to secure by Letters Patent is,

1. In a locking device for doors of electrically driven cars, the combination with an actuating member to be moved, an electrically actuated locking device, means for supplying current to said device from the main current supply when the car is electrically propelled and means for supplying current also to said device from a generator when the car is coasting.

2. In a locking device for doors of electrically driven cars, the combination with a rotatable shaft, a notched disk for said shaft, spring controlled means for engaging said notched disk, electrically actuated means including a block member for engaging said spring controlled means to form a locking device, and means for supplying current to said electrically actuated means when the car is coasting under its own momentum.

3. In a locking device for doors of electrically driven cars, the combination with a rotatable shaft and lock mechanism, including a lock dog and stop blocks, for locking said shaft against rotation when the car is in motion.

4. In an electrically operated lock mechanism for doors of electrically operated cars, a solenoid, a notched lock disk, a spring

pressed pivotally mounted lock-member normally engaging said notched lock disk and means for engaging said lock member against movement when the solenoid is energized.

5. In a locking device for doors of electrically driven cars, the combination with a rotatable shaft, a disk carried by said shaft, and provided with a jog therein, a dog normally adapted to lie in said jog and to be rotated upon rotation of said shaft, means adapted to prevent rotation of said dog, and electrically controlled means for locking said dog against rotation.
10. In a locking device for doors of electrically driven cars, the combination with a rotatable shaft, a disk carried by said shaft, and provided with a jog therein, a dog normally adapted to lie in said jog and to be rotated upon rotation of said shaft, means adapted to prevent rotation of said dog, and electrically controlled means for locking said dog against rotation.
15. In a locking device for doors of electrically driven cars, the combination with a rotatable shaft, a disk carried by said shaft, and provided with a jog therein, a dog normally adapted to lie in said jog and to be rotated upon rotation of said shaft, means capable of moving into the path of said dog, and electrically controlled means for locking said dog against rotation, and means for actuating said electrically controlled means
20. when the car is in motion.

25. In a locking device for doors of electrically driven cars, the combination with a rotatable shaft, a disk carried by said shaft, and provided with a jog therein, a dog nor-

mally adapted to lie in said jog and to be rotated upon rotation of said shaft, an obstruction block adapted to be positioned in the path of said dog to prevent the rotation thereof, a magnet for drawing said block into position to obstruct said dog, and means for normally withdrawing and retaining said block out of the path of said dog when the magnet is not energized.

30. In a locking device for doors of electrically driven cars, the combination with a rotatable shaft, a disk carried by said shaft, and provided with a jog therein, a dog normally adapted to lie in said jog and to be rotated upon rotation of said shaft, an obstruction block adapted to be positioned in the path of said dog to prevent the rotation thereof, a magnet for drawing said block into position to obstruct said dog, and means for normally withdrawing and retaining said block out of the path of said dog when the magnet is not energized.
35. In a locking device for doors of electrically driven cars, the combination with a rotatable shaft, a disk carried by said shaft, and provided with a jog therein, a dog normally adapted to lie in said jog and to be rotated upon rotation of said shaft, an obstruction block adapted to be positioned in the path of said dog to prevent the rotation thereof, a magnet for drawing said block into position to obstruct said dog, and means for normally withdrawing and retaining said block out of the path of said dog when the magnet is not energized.
40. In a locking device for doors of electrically driven cars, the combination with a rotatable shaft, a disk carried by said shaft, and provided with a jog therein, a dog normally adapted to lie in said jog and to be rotated upon rotation of said shaft, an obstruction block adapted to be positioned in the path of said dog to prevent the rotation thereof, a magnet for drawing said block into position to obstruct said dog, and means for normally withdrawing and retaining said block out of the path of said dog when the magnet is not energized.
45. In a locking device for doors of electrically driven cars, the combination with a rotatable shaft, a disk carried by said shaft, and provided with a jog therein, a dog normally adapted to lie in said jog and to be rotated upon rotation of said shaft, an obstruction block adapted to be positioned in the path of said dog to prevent the rotation thereof, a magnet for drawing said block into position to obstruct said dog, and means for normally withdrawing and retaining said block out of the path of said dog when the magnet is not energized.
50. In a locking device for doors of electrically driven cars, the combination with a rotatable shaft, a disk carried by said shaft, and provided with a jog therein, a dog normally adapted to lie in said jog and to be rotated upon rotation of said shaft, an obstruction block adapted to be positioned in the path of said dog to prevent the rotation thereof, a magnet for drawing said block into position to obstruct said dog, and means for normally withdrawing and retaining said block out of the path of said dog when the magnet is not energized.

In testimony whereof I have hereunto set my hand on this 1st day of April, A. D. 55
1919.

RAYMOND H. PARSONS.
